(57) **CLAIM**

The ornamental design for a retainer for a linear guide unit as shown and described.

DESCRIPTION

1. Retainer for a linear guide unit

1.1: Front

1.2: Back

1.3: Top

1.4: Bottom

1.5: Enlarged

1.6: Enlarged

1.7: Cross sectional

1.8: Cross sectional

1.9: Enlarged

1.10: Enlarged

1.11: Enlarged

1.12: Right

1.13: Left

1.14: Reference view

1.15: Reference view

The broken lines do not form part of the claimed design; the dash-dot lines represent the boundary between the claimed design and unclaimed design and form no part of the claimed design; reproduction 1.5 is enlarged perspective view of portion A-A in reproduction 1.1; reproduction 1.6 is enlarged front view of portion A-A in reproduction 1.1; reproduction 1.7 is cross-sectional view of C-C in reproduction 1.6; reproduction 1.8 is cross-sectional view of B-B in reproduction 1.6; reproduction 1.9 is enlarged back view of portion A-A in reproduction 1.1; reproduction 1.10 is enlarged top view of portion A-A in reproduction 1.1; reproduction 1.11 is enlarged bottom view of portion A-A in reproduction 1.1; reproduction 1.14 is a reference view showing a state in use and forms no part of the claimed design; reproduction 1.15 is a reference view showing a state in use and forms no part of the claimed design.

1 Claim, 15 Drawing Sheets
